(57) **CLAIM**

The ornamental design for a ceiling fan housing, as shown and described.

DESCRIPTION

FIG. 1 is a bottom perspective view of a ceiling fan housing in accordance with my design;

FIG. 2 is a reduced top plan view of the ceiling fan housing in accordance with my design;

FIG. 3 is a reduced bottom plan view of the ceiling fan housing in accordance with my design;

FIG. 4 is an enlarged side elevation view of the ceiling fan housing in accordance with my design, all sides being identical;

FIG. 5 is a greatly enlarged side elevation view of the ceiling fan housing in accordance with my design, all sides being identical; and,

FIG. 6 is a greatly enlarged bottom plan view of the ceiling fan housing in accordance with my design.

The broken line showing of the canopy, blades and blade irons is included for the purpose of illustrating environmental structure and forms no part of the claimed design.
